UNITED STATES PATENT OFFICE.

GEORGE W. BAKER, OF JEANNETTE, PENNSYLVANIA, ASSIGNOR TO NORTHWESTERN EXPANDED METAL COMPANY, OF CHICAGO, ILLINOIS, A CORPORATION.

MACHINE FOR MAKING RIBBED EXPANDED METAL.

Application filed December 27, 1921. Serial No. 524,881.

To all whom it may concern:

Be it known that I, GEORGE W. BAKER, a citizen of the United States, and a resident of Jeannette, county of Westmoreland, and 5 State of Pennsylvania, have invented certain new and useful Improvements in Machines for Making Ribbed Expanded Metal, of which the following is a specification.

The present invention relates to machines 10 for operating upon metal sheets that are previously cut or slashed to form longitudinally and alternately disposed slitted and unslotted panels or strips and which machines have means for expanding the slitted panels of the sheet as the latter is continuously advanced, and preferably also have means for shaping the unslotted panels or strips into strengthening ribs. The invention seeks to provide improved means 15 for expanding or opening the slitted portions of such sheets into uniform diamond mesh. More particularly the object of the invention is to adapt such improved means to a machine for forming ribbed expanded metal of the type shown in the U. S. Letters Patent of F. C. Arey, No. 1,318,953, dated October 14, 1919. The invention consists in the features hereinafter set forth, illustrated in the preferred 20 embodiment in the accompanying drawings and more particularly pointed out in the appended claims.

In the drawings:—

Fig. 1 is an elevation of the expanding portion of a machine of the type set forth in the above noted Arey patent and to which the present invention is applied, the front wall of the expander head being broken away.

Fig. 2 is a horizontal section on the line 2—2 of Fig. 1.

Fig. 3 is an enlarged detail elevation of a portion of the expander mechanism looking in a direction at right angles to the 45 plane of movement of the unexpanded sheet, or in the direction of the arrow 3 in Fig. 4.

Fig. 4 is a detail plan of the parts shown in Fig. 3.

Fig. 5 is a view in elevation and Fig. 6 50 is a perspective view of one of the expansion plates.

Figs. 7 and 8 are detail sections on the ones 7—7 and 8—8 respectively of Fig. 6.

The machine comprises a suitable base upon one end of which is mounted a hollow 55 expander head 1. As in the machine set forth in the Arey patent the expander head is provided at one end with a pair of vertical feed rolls 2 and, within the head are arranged a number of sets or pairs of rolls 60 3 having vertical axes and disposed in a row and in an inclined stepped series. A set of horizontal, parallel guides or deflecting devices 4 extend through the outer or front side of the head, these guides being arranged 65 in angular relation to the row of rolls 3 and in a corresponding stepped series.

The metal sheets, which are previously cut or slashed to form slitted panels A and intermediate unslotted panels or strips B 70 (see Fig. 3), are fed on edge or in a vertical plane between the rolls 2 which are of sufficient length to accommodate the widest sheet to be expanded. Each set of the stepped series of rolls 3 project downwardly 75 below the next set and, while the extent of projection of the rear roll may be more, that of the outer or front roll of each set is equal to the combined width of one of the slitted panels and one of the unslotted strips 80 of the sheet. Preferably also the sets of rolls overlap in vertical direction and are of such width that each set overlaps and engages one of the slitted panels of the sheet and the two adjacent unslotted strips. 85

The guides or deflecting devices 4, each of which comprises a front rail and a back rail, extend respectively into snug relation with the lower ends of the back and front rolls 3 of the corresponding set at the delivery side of the bight of the rolls. The rails of each guide are spaced apart to form a guide-way or pass disposed in a vertical plane and tangent to the front roll of the corresponding set, the guide-way or pass 90 having a width and depth which substantially correspond to the thickness of the metal sheet and the width of an unslotted strip or panel respectively.

As the unslotted panels or strips of the sheet pass beyond the lower ends of the rolls 3, they are deflected laterally at different points in the path of travel of the sheet into the parallel vertical passes of the guides and the intermediate slotted panels are expanded. During this opera- 100 105

tion, as one of the unslotted panels passes the lower end of a set of rolls 3 it enters the corresponding guide 4 while the adjacent portion of the unslotted panel next 5 above is held between this set of rolls and the next set before it passes into the next guide, and as two adjacent unslotted panels enter the corresponding guides at different points in their path of travel, the mesh sections 10 of the slotted panels between these parts are deflected laterally from the plane of the sheet and the slits are expanded or opened to form diamond mesh. The extent of expansion depends upon the angle between 15 the guides or deflecting devices 4 and the plane of movement of the unslotted sheet as it is advanced by the rolls 2 and 3. Preferably this angle is about 30 degrees.

In accordance with the present invention, 20 a series of devices or expansion plates are provided for guiding or predetermining the paths of movement of the mesh sections of the slotted panels as they are expanded. In the preferred embodiment shown, these guiding devices or expansion plates comprise irregular shaped pieces 5 of hardened steel arranged between the outer or front rolls 3 and which are provided with flat, vertical faces *a* tangent to these rolls. In the construction shown, the number of guides 4 exceed by one the number of sets of rolls 3 and the upper expansion plate 5 extends between the upper set of rolls and the upper guide, which is disposed in horizontal alignment 30 with the upper portion of the upper or last set of rolls.

Each of the expansion plates is wider at one end than the other and is so arranged that the lower edge *b* of its vertical face *a*, and 40 also its lower face *c*, extend upwardly at an angle from the lower to the upper of the two rolls between which it is arranged. The vertical face *a* of each expansion plate is adapted to overlie and engage one of the slotted panels of the sheet as the latter passes beyond the corresponding set of rolls 3. Preferably also each expansion plate is 45 of such width that its vertical face overlies the portion of the unslotted panel of the sheet that is engaged by the two adjacent sets of rolls, and the plates form in effect the front rails of a series of short guides arranged between the sets of rolls 3, the back rails 6 of which are disposed between 50 the rear rolls of the series. It will also be noted that the upper expansion plate and the associated guide thus form in effect an extension of the upper guide 4. The plates 5 and guides 6 are held in position in any 55 suitable manner, for example, by a series of vertical supports 7 and 8 to which they are secured. The supports in turn are secured to suitable ribs or lugs (not shown) cast upon the internal walls of the expander head. Each plate in the form shown is cut

away to form a seat *d* for receiving the lower end of the corresponding support 7, to which it is removably secured. Preferably the angle between the vertical and horizontal faces of each plate and which form its inclined edge *b* is quite sharp, but any burr or roughness which might tend to cut the metal on this edge is removed. To reduce wear upon the edges *b* of the expansion plates the latter, as stated, are preferably formed of hardened tool steel but, in order that they may be readily renewed when these edges are worn, the plates, as noted, are removably secured in position.

The wider end of each expansion plate 5 and the adjacent end of the corresponding guide 6 are curved to fit against the faces of the lower of the two sets of rolls between which they are arranged and the edge portions of the vertical faces of the plates and guides adjacent these rolls are slightly rounded and serve to strip the portions of the sheet which they engage from the rolls. The concave end face of one of the end plates is indicated at *e* in Fig. 5. The narrow opposite end of the plate is cut away as at *f* so that the plate can extend beneath the next higher front roll 3.

The slotted panels of the metal sheet are as usual provided with slits arranged in rows 95 with bonds between the slits of each row and opposite the slits of adjacent rows. With this arrangement the slits in adjacent rows are disposed in inclined series, and each inclined series is adapted to be expanded to form an inclined row of diamond shaped openings. In Fig. 3, line *t* indicates an inclined series of slits, and in Fig. 4 the line *t'* indicates an inclined row of diamonds.

The angling or inclination of the edges *b* of the expansion plates corresponds to the angle of the inclined series of slits of the sheet, and the rolls 3, guides 4 and expansion plates 5 are so located that, as each inclined series of slits passes over the edge *b* of the corresponding expansion plate, the portions of the unslotted panels at opposite ends of a series will be engaged by the rolls 3 of two adjacent sets and deflected through the corresponding guides 4. The expansion plates 5, the co-operating guide rails 6 and the rolls 3 thus hold the mesh sections of each slotted panel in a fixed plane and the successive inclined series of slits against expansion until each such complete series 115 reaches and passes over the edge *b* of the corresponding expansion plate. In other words, the arrangement serves to hold each inclined series of slits against expansion until the expansion force can be simultaneously applied to each entire series. This arrangement prevents the sheet from slipping down and causes the expansion force to be applied at substantially 90° to the plane of the unexpanded portions of the slotted 120

130.

panels, to successively open the inclined series of slits of each panel one at a time. By thus applying the expansion force simultaneously to each complete inclined series of slits, 5 they are opened or expanded uniformly and to a maximum extent as they pass over the edges of the expansion plates and a set is given to the expanded mesh.

As shown in Figs. 3 and 4, an expanded 10 panel of the sheet comprises inclined strands s which extend between the marginal unslotted strips and are connected to one another by substantially horizontal strands s' . In Fig. 3 the diagonal and connecting 15 strands are indicated by unshaded and shaded portions respectively. It may also be noted that the metal between two adjacent inclined series of slits forms a diagonal strand and one series of connecting strands. 20 The present construction is designed to effect the expansion of the slotted panels of the sheet by bending the connecting strands s' and without stretching the strands. It is noted, to this end, that the rolls, guides and 25 expansion plates are so located that the horizontal distance between the axes of two adjacent sets of rolls 3 and between the ends of two adjacent guides, corresponds to the horizontal distance between the ends of an 30 inclined series of slits in one of the slotted panels of the sheet, and that the inclined edge b of each expansion plate lies along an inclined line x (see Fig. 3) that intersects the vertical lines y at the bights of two adjacent sets of rolls at points which are also intersected by the paths of movement of the opposite margins of the corresponding slotted panel. In other words, the diagonal 35 distance between the points at which two adjacent sets of rolls register with the margins of a slotted panel, and which is indicated in Fig. 3 by line x , is equal to the length of a diagonal strand or of a diagonal row of slits, and the edge b of the expansion plate lies along or coincides with the line x and corresponds to the inclination of the diagonal strands and series of slits. 40 With this arrangement each diagonal strand and each diagonal series of slits of the 45 slotted panels of the sheet pass simultaneously over the inclined edge b of the corresponding expansion plate and each entire inclined strand s is deflected from the original plane of the sheet by bending the connecting strands s' . Thus the successive inclined strands and inclined series of slits are held against expansion until they reach lines x , at which time the portions of the unslotted strips at the end of each such series 50 are deflected from the original plane of the sheet at lines y . It is also noted that the edges b of the expansion plates about which the inclined panels of the sheet are deflected and expanded, are arranged in an inclined series of inclined steps that are vertically

spaced apart a sufficient distance to permit the proper deflection of the unslotted panels about the vertical lines y . In other words, the entire sheet is progressively deflected about a continuous line which extends at 70 right angles across the paths of movement of the unslotted panels and at an acute angle across the paths of movement of the slotted panels and which acute angle, as noted, corresponds to the inclination of the inclined 75 series of slits in the unexpanded sheet.

As noted, the foregoing arrangement permits the expansion of the slotted panels by the bending of the connecting strands and without stretching the metal. To prevent 80 the expansion from stretching the metal the strands which merge into the unslotted strips, the intermediate panels are angularly slotted, that is the parallel rows of slits of the panels are slightly inclined relatively to the longitudinal margins of the sheet as shown in Fig. 3, the angle of inclination being determined by the relation between the transverse spacing of the rows of slits and the longitudinal spacing between 85 the centers of the bonds. With the slits thus disposed each inclined series, which comprises a slit in each row and is adapted to form a diagonal row of diamond mesh, are inclined in the same direction as the rows 90 of slits but at an angle equal to twice that at which the individual rows of slits are inclined. It is also noted that, as indicated in Fig. 3, the sheet is fed into the machine in such a position that the rows of slits are 95 inclined in the same direction as the edges b of the expansion plates 5, but the latter are inclined at a greater angle which, as already noted, corresponds to the angle of inclination of the inclined series of slits. 100

With this arrangement the expansion throughout the width of the panels is effected by bending and without materially stretching the strands. Moreover, after the deflection of the unslotted strips to effect the 110 expansion of the slotted panels, the strips are maintained substantially straight in longitudinal direction and are not corrugated or shortened.

Preferably the peripheral portion of one 115 of the rolls of each of the sets of rolls 2 and 3, is provided with annular ribs 9 and the companion rolls are provided with corresponding grooves which serve to form or engage previously formed shallow ribs in 120 the unslotted panels or strips of the metal sheet, the ribs in the construction shown being formed upon the front roll of each set. Preferably also the guides 4 and 6, additional guides 6' for the unslotted strips 125 and the feed rolls 2 are provided with similar ribs and grooves. By this means the displacement of the sheet from proper position by the force applied to expand the slotted panels is prevented. The guides 6' 130

for the unslotted strips of the sheet extend between the set of feed rolls 2 and the stepped series of rolls 3. In Fig. 2, for the sake of clearness, only one such guide is shown.

The ribbed rolls and guides serve to hold the sheet in proper position relatively to the expansion plates and deflecting devices and by means of the improved machine the 10 rapid expansion of comparatively light gauge metal sheets having slotted and unslotted panels can be effected without stretching the strands.

Sets of rolls 11 are preferably provided at 15 the delivery ends of the guides 4 and these rolls assist in advancing the sheets and also in completing the shaping of the unslotted panels into stiffenings ribs. The machine may also be provided with additional finishing and straightening rolls. Such additional rolls are set forth in the Arey patent above noted, which also discloses suitable means for operating the rolls at proper speeds. As set forth in that patent, the 20 rolls 2 and 3 are driven from the main shaft 12 through vertical and horizontal counter-shafts 13 and 14 which are connected together and to the front or driving roll of each set by spiral gears. Also as set forth 25 in the Arey patent, the two rolls of each set are connected by spur gears and what has been termed as the rear roll of each set, is journaled in spring-pressed bearings.

Changes may be made in the details set 30 forth and the invention applied to different types of machines for expanding sheets have slotted and unslotted panels without departure from the essentials of the invention as defined in the claims.

40 I claim as my invention:

1. In a machine for expanding sheet metal having angularly slotted panels and unslotted strips, the combination with feeding means for continuously advancing the 45 sheet and means for guiding and deflecting adjacent unslotted strips into different parallel planes with the strips straight in longitudinal direction to thereby expand the slotted panels, of a series of guides angularly disposed between the paths of movement of the strips and over which the mesh sections of the slotted panels are deflected and simultaneously expanded.

2. In a machine for expanding sheet 55 metal having angularly slotted panels and unslotted strips, the combination with means for feeding the sheet and parallel spaced guides for deflecting the unslotted strips to thereby expand the panels, of a series of 60 expansion plates arranged between said guides and over which plates the slotted panels are longitudinally and continuously advanced, said plates having inclined edges over which the mesh sections of the slotted 65 panels are deflected laterally from one fixed

plane to another and simultaneously expanded by bending and without stretching the strands thereof.

3. In a machine for expanding sheet metal having angularly slotted panels and unslotted strips, the combination with means for continuously and longitudinally feeding the sheet and means for deflecting, but without shortening, the panels and strips about a continuous line extending at right angles 75 across the paths of movement of the unslotted strips and at an acute angle across the paths of movement of the slotted panels and a series of guides arranged to engage and hold the mesh sections of the slotted panels against expansion until they reach the inclined portions of said line.

4. In a machine for expanding sheet metal having angularly slotted panels and unslotted strips, the combination with means 80 for feeding the sheet and means for engaging the unslotted strips at different points in their paths of travel and deflecting them transversely of the plane of the sheet into parallel spaced planes with the strips 85 straight in longitudinal direction to thereby expand the panels, of a series of guides angularly disposed between the paths of movement of the unslotted strips and over each of which one of the slotted panels is deflected 90 from one fixed plane to another.

5. In a machine for expanding sheet metal having slotted panels and unslotted strips, the combination with means for feeding the sheet and a stepped series of guides 100 for engaging the unslotted panels at different points in their paths of travel and deflecting them out of the plane of the sheet into a series of parallel planes to thereby expand the intermediate slotted panels, of 105 a series of expansion plates arranged between said guides and over which plates the slotted panels are advanced, said plates having a series of angularly disposed edges arranged in an inclined series of steps and 110 over each of which one of the mesh sections of the slotted panels is deflected laterally from one fixed plane to another and simultaneously expanded.

6. A machine for expanding sheets that 115 are previously cut or slashed to form slotted panels and unslotted strips, comprising sets 120 of rolls and guides disposed in stepped series and arranged to continuously and longitudinally advance the sheet and progressively deflect the unslotted strips about lines at right angles to the direction of movement of the sheet to thereby expand the slotted panels, and a stepped series of guide plates 125 for controlling the expansion of the slotted panels having guiding edges lying along parallel lines that are inclined to the direction of movement of the sheet and intersect the ends of the lines about which the unslotted strips are deflected.

7. A machine for expanding metal sheets having slotted panels and unslotted strips, comprising sets of rolls arranged in stepped series, each set being arranged to engage one of the slotted panels of the sheet and the two adjacent unslotted strips, a stepped series of guides arranged to engage the unslotted strips as they pass the projecting ends of the sets of rolls and deflect the strips to thereby expand the slotted panels, and a stepped series of short guides disposed between the sets of rolls and each arranged to engage a slotted panel as it passes from the projecting portion of the corresponding set of rolls and the part of the unslotted strip passing between said set of rolls and the next adjacent set, said short guides having faces tangent to said rolls and inclined edges arranged in a stepped series and over which the mesh sections of the slotted panels are deflected and simultaneously expanded.
8. A machine for expanding metal sheets having alternate slotted panels and unslotted strips, comprising a stepped series of sets of rolls, each set being arranged to engage one of the slotted panels of the sheet and the two adjacent unslotted strips, and a corresponding stepped series of guides arranged to engage the unslotted strips as they pass the projecting ends of the sets of rolls to thereby deflect the strips and expand the slotted panels, said sets of rolls having ribs and grooves arranged to engage shallow ribs in the unslotted strips of the sheet.
9. A machine for expanding metal sheets having alternate angularly slotted panels and unslotted strips, comprising sets of feed- 40 ing rolls and guides arranged to continuously advance the sheet and deflect the strips into a series of parallel spaced planes to thereby expand the panels and a series of guiding devices having inclined edges over which the slotted panels are deflected 45 and simultaneously expanded, portions of the rolls and guides having co-operating ribs and grooves arranged to engage longitudinal ribs in the unslotted strips to thereby hold the sheet in position as the slotted 50 panels thereof are expanded.
10. A machine for expanding metal sheets having alternate slotted panels and unslotted strips, comprising sets of feed rolls and guides arranged to continuously ad- 55 vance the sheet and deflect the strips at different points in their paths of travel into a series of parallel spaced planes to thereby expand the panels, the portions of the rolls and guides arranged to engage the unslotted 60 strips at the points of deflection having co-operating ribs and grooves for engaging longitudinal ribs in the strips and thereby hold the sheet in position as the slotted panels thereof are expanded.

GEORGE W. BAKER.
